US0D1087472S

(12) **United States Design Patent** (10) **Patent No.:** **US D1,087,472 S**
(45) **Date of Patent:** **** Aug. 5, 2025**

(54) **SAFETY GARMENT**

(71) Applicant: **Honeywell International Inc.**,
Charlotte, NC (US)

(72) Inventors: **Yiwen Lin**, Shanghai (CN); **Hongbing Xiang**, Shanghai (CN); **Jiawei Liu**, Shanghai (CN); **Qiang Pan**, Shanghai (CN)

(**) Term: **15 Years**

(21) Appl. No.: **29/850,119**

(22) Filed: **Aug. 17, 2022**

(51) **LOC (15) Cl.** **02-02**

(52) **U.S. Cl.**

USPC **D29/100**

(58) **Field of Classification Search**

(57) **CLAIM**

The ornamental design for a safety garment as shown and described.

DESCRIPTION

FIG. 1 is a front elevation view of a safety garment showing the new design;

FIG. 2 is a rear elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The broken lines illustrate portions of the safety garment that form no part of the claimed design.

1 Claim, 5 Drawing Sheets
